CHAIN LINK

Edward A. Graetz, Pound, Wis., assignor to Graetz Manufacturing, Inc., Pound, Wis.

Filed Nov. 3, 1969, Ser. No. 19,890

Term of patent 14 years

Int. Cl. D8—03

U.S. Cl. D8—261

FIG. 1 is a plan view of a chain link;
FIG. 2 is a side view thereof;
FIG. 3 is a bottom view thereof;
FIG. 4 is a side view thereof taken from the side opposite to the FIG. 2 showing;
FIG. 5 is an end view thereof;
FIG. 6 is a view from the end opposite to that shown in FIG. 5;
FIG. 7 is a sectional view taken along line 7—7 in FIG. 1.

I claim:
The ornamental design for a chain link, substantially as shown.
